ADJUSTABLE MOUNTING FOR ELECTRIC MOTORS

Carl G. H. Anderson and Ivar K. Fog, Toronto, Ontario, Canada, assignors to Sangamo Company Limited, Toronto, Ontario, Canada

Application February 4, 1938, Serial No. 188,594

4 Claims. (Cl. 248—23)

The principal objects of this invention are to overcome the difficulties met with in providing means for maintaining the required tension on the motor driven belt and in maintaining the proper alignment of the motor pulley with the driven member, and to provide a motor mounting which will automatically adjust itself to variable conditions affecting the drive.

The principal feature of the invention consists in securing one end of a flexible plate to the motor shell and securing the other end of said plate to a base to permit a rolling movement of the motor and applying a spring effort to roll the motor and apply tension to the drive belt connected to the motor.

In the accompanying drawing Figure 1 is an end elevational view showing a motor and mounting exemplifying the present invention.

Figure 2 is a side elevational view of the motor and mounting shown in Figure 1.

Figure 3 is a plan view.

Figure 4 is a plan view illustrating a slightly modified construction.

Figure 5 is an enlarged partial end elevation of the modified structure shown in Figure 4.

Figure 6 is an end elevation showing a further modification of mounting.

In the use of small electric motors for driving devices such as washing machines or refrigerator mechanisms it is customary to operate the driven mechanism from the motor through the medium of a belt, and belt drives are subject to great variation which results in loss of efficiency, and in making adjustments much difficulty is experienced both in obtaining the proper tension and in maintaining the alignment of the driving and driven members.

Further, adjustments may be made under temperature and humidity conditions which may almost immediately become inoperative by reason of uncontrollable changes in surrounding atmospheric conditions.

The present invention contemplates an extremely simple device which, as illustrated in Figures 1, 2, and 3, comprises a pair of flat flexible plates 1 of metal or other suitable material having their ends 2 secured to the shell 3 of the motor by being welded or riveted or held by screws 4. These plates extend under the motor shell in the direction of the belt drive 5 to the driven member (not shown), and their other ends are fixed to the base 6 by suitable bolts or other means 7.

A plate 8, also of flexible material may be placed between the plates 1 having one end 9 se-

cured to the motor shell at the side opposite to the points of securing the plates 1. This plate extends under the motor in a direction opposite to the drive belt, and its end 10 is secured to the base by bolts 11.

The motor when thus secured may roll on its flexible supports but its shifting axis will always move to parallel positions and the motor cannot shift sideways.

Suitable arms 12 are provided on the end 10 housings to extend in a direction away from the drive belt 5, and coiled tension springs 13 are connected to the ends of said arms and to the base, thus applying a force tending to roll the motor away from the drive belt and automatically maintain a tension on the belt equal to the tension of the springs so that the belt will be maintained in its most effective operative condition whether it shrinks or expands and wear will be automatically compensated for.

It may be found desirable to dispense with the centre plate 8 and connect the two plates at opposite ends to the motor housing as illustrated by the dotted lines in Figure 4.

In Figure 5 the holding plates as shown in Figure 4, are arranged at either side of a pad 14 which may be of sound deadening material, such as rubber compressed between the base and motor and a sound deadening strip 15 may be arranged between the motor shell and holding plates.

The spring tension device as shown is very simple and inexpensive. A more simplified but efficient structure is illustrated in Figure 6 in which the motor is mounted on a single curved spring plate 16, one end of which is curved upwardly and is secured to the motor shell on the side away from the drive belt, the other end being fastened rigidly to the base.

In this form of application of the invention the motor is located in a position where it has to be rolled toward the driven member in order to place the belt in position, and the applied tension on the curved spring plate will exert a downward pressure substantially at right angles to the line of pull of the drive belt. The result is that the curved end of the spring plate 16 is always exerting a constant self-compensating pull on the belt and the downward component of forces holds the motor firmly against the base block and prevents vibration.

The exemplary forms of supports described will provide in effect a floating mounting insofar as displacement of the motor bodily in the plane of disposition of the belt drive is concerned. Full

advantage may therefore be taken of the reactance torque thrust of the motor to roll the motor bodily in a belt-tightening direction and since this torque is greatest at the moment of starting when the load is greatest, an efficient belt drive will be achieved.

It will be readily appreciated that other forms of application of this invention may be devised without departing from the principal feature as herein set forth.

What we claim as our invention is:

1. In a motor mounting, a motor, a base, means for mounting said motor for substantial rolling action relative to said base, including spaced-apart spring strips forming a resilient anchorage between the base and motor, and a third spring strip disposed intermediately between the aforesaid spring strips in resilient opposition thereto and co-operating with the motor and with said pair of spring plates and resiliently supporting a portion of the motor weight, all of said spring strips being individually formed and separately secured to the motor at points offset longitudinally of the axis thereof.
2. Means for adjustably mounting an electric motor on a base for substantial rolling action relative to the base in a direction transversely of the axis, including means forming a resilient cradle support for said motor with the lower ex-

tremity of the motor spaced only slightly above the base, said cradle support including separate curved spring plates secured at opposite ends in oppositely disposed relation to opposite sides of the motor and to said base.

3. In a motor mounting, a motor, a base, means for resiliently supporting said motor for substantial rolling action relative to said base including spaced-apart spring strips secured to the side of the motor below the level of the axis and extending tangentially under the motor and rigidly secured to the base at the opposite side of securing to the motor and forming a resilient support and anchorage between the base and motor, and resilient means interposed under tension between said spaced-apart spring strips and between the lower periphery of the motor and the base and resiliently relieving said spring strips of the full weight of the motor.

4. In combination with a motor and base, and means resiliently mounting said motor on the base for rolling displacement, a pad of resilient material interposed between the base and the lower periphery of the motor and forming a cushioning roller support for said motor and relieving said resilient mounting means of the full weight of the motor.
